(57) **CLAIM**

The ornamental design for a camera as shown and described.

DESCRIPTION

FIG. 1 is a front elevation view of a camera showing a first embodiment of the claimed design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a bottom, front and left side perspective view thereof;

FIG. 8 is a top, front and right side perspective view thereof; and

FIG. 9 is a bottom, rear and right side perspective view thereof.

FIG. 10 is a front elevation view of a camera showing a second embodiment of the claimed design;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a bottom, front and left side perspective view thereof;

FIG. 17 is a top, front and right side perspective view thereof; and

FIG. 18 is a bottom, rear and right side perspective view thereof.

FIG. 19 is a front elevation view of a camera showing a third embodiment of the claimed design;

FIG. 20 is a rear elevation view thereof;

FIG. 21 is a left side elevation view thereof;

FIG. 22 is a right side elevation view thereof;

FIG. 23 is a top plan view thereof;

FIG. 24 is a bottom plan view thereof;

FIG. 25 is a bottom, front and left side perspective view thereof;

FIG. 26 is a top, front and right side perspective view thereof; and,

FIG. 27 is a bottom, rear and right side perspective view thereof.

(Continued)

The broken lines depict portions of the camera that form no part of the claimed design.
